FIBERBOARD CONTAINER HAVING REINFORCED ENDS AND INTEGRAL HINGED CLOSURE

Walter G. Glascoff, Jr., and Charles W. Evert, Milwaukee, Wis., assignors to Downing Box Company, Milwaukee, Wis., a corporation of Wisconsin

Application January 12, 1945, Serial No. 572,444

9 Claims. (Cl. 229—23)

1

This invention relates to improvements in containers, and more particularly to containers adapted for the transportation and handling of bottled or canned beverages such as beer.

Containers formed of fiberboard have in recent years, because of their relatively inexpensive nature and lightness in weight, become increasingly popular for use as beverage cases in lieu of the wooden boxes formerly employed. Two types of fiberboard containers are commonly used. One type, the single shipment variety, is formed of relatively light-weight fiberboard and is of a very inexpensive nature. The other type, with which the present invention is concerned, must be constructed to stand up satisfactorily when re-used seven or eight times. Containers of this latter variety as heretofore constructed have, however, been objectionable for a number of reasons. Inasmuch as it is common practice to pick up a beverage case by the hand hole of one end wall only, a great deal of strain is placed on said end wall, causing tearing, particularly at the corners. In addition, the usual fiberboard container of this type will not withstand a large amount of inward pressure on the side or top and will not withstand pressures applied to two diagonally opposite corners. Furthermore, difficulty has been encountered in maintaining the hinged covers against popping open during handling.

It is, therefore, a general object of the present invention to provide an improved fiberboard container which is constructed in a novel manner to provide greater rigidity in all directions. Thus the box will withstand the usual rough handling, the containers can be stacked one on top of another without fear of crushing those below, and the containers cannot be injured when pressures of the usual type are applied to two diagonally opposite corners.

A further object of the invention is to provide a container including complementary hinged covers, the covers and end walls being constructed in a novel manner to cooperate with each other in producing a bracing effect against both inward and outward strains when the covers are closed.

A further object of the invention is to provide a container of the class described wherein the covers are maintained firmly in position even when the box is subjected to diagonal pressures.

A further object of the invention is to provide a container formed of fiberboard or the like which has such strength, rigidity, and resistance to tearing or breaking forces that it can be re-used a relatively large number of times.

A more specific object of the invention is to

2

provide a container, as above described, having complementary hinged covers wherein each cover member is formed with side and end flanges, and wherein the container end walls are provided with upper edge slots for receiving the meeting side flanges and with upper edge grooves or channels for receiving the end flanges of the cover members. The construction of the present invention is an improvement over the construction of Richards and Evert application, Serial No. 521,936, filed February 11, 1944, now matured into Patent No. 2,382,819, and Richards and Evert application, Serial No. 545,792 filed July 20, 1944, now matured into Patent No. 2,387,184, in that the end walls are so formed as to increase the rigidity thereof and provide a smooth external surface. The upper edge cover flange-receiving channels are concealed from view when looking at an end of the box, and the channels do not provide projections from the ends of the container which might catch on objects during handling and cause damage to the container. Furthermore, the construction is such that the channels are braced against outward flexing.

3

A further and more specific object of the invention is to provide a construction wherein each end wall channel is preferably formed integral with and is embraced by inner and outer end wall layers, each channel including a portion bent

4

30 downwardly from the upper edge of an inner end wall layer and then upwardly to join the upper edge of an outer end wall layer, the upper edge of the inner layer and the downwardly bent channel-forming portion being provided with an upper edge slot.

5

A further specific object of the invention is to provide a container as above described, having end wall channels, wherein the horizontal fold line between the downwardly and upwardly bent

40 channel-forming parts is slotted at its ends for receiving the upper portions of the side wall flanges in a "Bliss" type of box. Thus, the upper ends of these side wall flanges are received between the downwardly and upwardly bent portions of the channels and the remainder of each side wall flange is embraced between the inner and outer end wall layers. By this arrangement the downwardly and upwardly bent channel-forming portions are held in properly separated

45

50 condition for readily receiving the end flanges of the cover members. Furthermore, the end wall channels do not project an undesired distance beyond the surfaces of the inner layers of the end walls, and said channels are neatly concealed between the inner and outer end wall layers.

With the above and other objects in view the invention consists of the improved container and all its parts and combinations, as set forth in the claims and all equivalents thereof:

In the accompanying drawings illustrating one complete embodiment of the preferred form of the invention, in which the same reference numerals designate the same parts in all of the views:

Fig. 1 is a perspective view of the container with the cover sections open;

Fig. 2 is an end view with the covers closed, parts being broken away;

Fig. 3 is a fragmentary vertical sectional view taken on line 3-3 of Fig. 2;

Fig. 4 is a sectional view taken on line 4-4 of Fig. 3;

Fig. 5 is a plan view of one of the cut and scored end wall blanks before folding; and

Fig. 6 is a perspective view of the blank of Fig. 5 after the upper edge portions have been folded to form a channel.

Referring more particularly to the drawings, the box illustrated is of the "Bliss" type, but features of the invention are obviously applicable for use in other types of boxes. The container comprises side walls 11 and 12 foldably connected to opposite edges of a bottom wall 13, cover members 14 and 15 foldable toward one another from the upper edges of the side walls 11 and 12, and plural thickness end walls 16 and 17 secured by metal stitching 18, or in any other suitable manner, to stitching flaps 19 and 20. The side walls, bottom wall, end walls and cover are preferably formed of solid fiberboard. They may, however, be formed of corrugated board or other suitable material of like nature.

The cover section 14 has its outer edge formed with a right-angularly bent side flange 21 and has its end edges formed with end flanges 22. Tongues 23, bent at right angles to the end flanges 22, are stapled as at 24 to the ends of the side flange 21. In order to obtain maximum reinforcement at the free edge of the cover member and provide extra material for a yielding angular tongue 21', the side flange 21 is of greater depth than the end flanges 22. Furthermore, the ends of the side flanges are cut down in depth, as at 25, to coincide with the depth of the tongues 23. The other cover member 15 is similarly formed with a side flange 26 having an angular yielding tongue 26', and with end flanges 27 having tongues 28 which are stapled to the ends of the side flange as at 29. The ends of the side flange 26 are cut down in depth as at 30.

The end walls 16 and 17 are identical in construction and, therefore, the description of one end wall will suffice. Referring to Figs. 5 and 6 the end wall blank has an inner hand hole 31 and also has spaced parallel lines of scoring 32, 33 and 45 which define an inner end wall layer 46, a downwardly foldable channel-forming portion 34 and an upwardly foldable channel-forming portion 35, and an outer end wall layer 47 having an outer hand hole 48. Midway between the sides of the blank is a slot which crosses the line of scoring 32. This forms a slot portion 36 extending downwardly from the score line 32 in the end wall layer 46 and a slot portion 37 which extends downwardly in the channel-forming portion 34 and which registers with the slot portion 36 when the blank is folded, as in Fig. 6. In addition, there are horizontal slots 38 at the ends of the score line 33 between the downwardly and upwardly foldable portions 34 and 35.

When the end walls are assembled in the container the downwardly folded channel-forming portions 34 contact the inner sides of the upper edges of the flanges 19 connected with the side walls, as is clear from Figs. 1 and 2. The upwardly folded channel-forming portion 35 contacts the outer sides of the upper ends of the side wall flanges 19. This arrangement is permitted by the slots 38, which slots receive the upper ends of the flanges 19. Thus these upper ends of the flanges 19 space the two portions 34 and 35 of the channels a required distance apart. In addition, this arrangement prevents the channel-forming members from projecting too far outwardly from the ends of the box. The outer end wall layer 47 is folded downwardly on the outer sides of the flanges 19 and 20 to conceal the latter and the folds 34 and 35. Thus the end walls present a smooth appearance and there are no projections to catch on objects during use. Staples 49, which extend through the outer layer 47, through the ends of the channel-forming portion 35, through the upper ends of the flanges 19, through the ends of the channel-forming portion 34, and through the inner end wall layer, maintain the end wall channels in assembled position. The staples 49 pass through the end wall layer 47, through the flanges 19 and 20 and through the layer 46.

When the cover sections 14 and 15 are closed, the cut-down portions 25 and 30 of the cover side flanges 21 and 26, together with the inwardly bent tongues 23 and 28, are received in the downwardly extending slots of the end walls, as is illustrated in Figs. 2, 3 and 4. These slots are formed by portions 36 extending downwardly from the upper edges of the end walls and by portions 37 extending downwardly in the downwardly foldable channel-forming part 34. At the same time the end flanges 22 and 27 of the cover members are received within the end wall channels. The parts are so arranged so that these cover end flanges readily enter the channels. On the other hand the spacing is such that when fully inserted in the channels they are frictionally maintained in position. Furthermore, the meeting flanges 21 and 26 of the two cover members frictionally engage one another in closed position and are also frictionally held in the end wall slots.

Due to the novel use of the plural thickness end wall layers which embrace and conceal the end wall channels, together with end wall slots, the container possesses unusual rigidity. The side flanges 21 and 26 of the covers reinforce the covers against downward pressure and also strengthen the box against inward pressures on the end walls. Such inward pressure is also prevented because of the engagement of the cover end flanges in the channels. At the same time the channels embraced between the plural layers prevent outward strains on the end walls from causing the end walls to bow outwardly. Due to the snug fit of all of the parts, when in closed position, the container is strongly braced against diagonal pressures. Furthermore, the possibility of the cover members popping open during handling is minimized.

Although only one form of the invention has been described, it is obvious that various changes and modifications may be made without departing from the spirit of the invention. For example, the end wall members of Fig. 6 may be formed of other material than paper board which 75 has been molded to provide the upper edge chan-

nels and the side and bottom groove for receiving the flaps 19 and 20 of a "Bliss" box. In addition, the construction as to certain features may be employed in boxes other than the "Bliss" type.

What we claim is:

1. In a container having side and end walls, each end wall comprising inner and outer layers and the inner layer of each end wall having an upper edge portion folded downwardly and then upwardly to join the upper edge of the outer layer and provide an upwardly opening channel between the two layers, complementary cover members hinged to said side walls and foldable toward one another over the container, and end flanges on each cover member which are received in said end wall channels when the members are closed.

2. In a container having a bottom provided with end flaps and having side walls provided with end flaps, end walls for the container, each end wall comprising an inner and outer layer with the end flaps of the side and bottom wall received between said inner and outer layers, means between said layers providing an upwardly opening channel at the upper edge of each end wall, complementary cover members hinged to said side walls and foldable toward one another over the container, and end flanges on each cover member which are received in said end wall channels when the cover members are closed.

3. In a container having side and end walls, each end wall comprising inner and outer layers and the inner layer of each end wall having an upper edge portion folded downwardly and then upwardly to join the upper edge of the outer layer and provide an upwardly opening channel between the two layers, there being a slot extending downwardly from the upper edge of the inner layer of each end wall and there being a registering slot formed in the downwardly folding part of each channel, complementary cover members hinged to said side walls and foldable toward one another over the container, and side and end flanges on each cover member, the ends of said side flanges being received in the upper edge slots of the end walls and said end flanges being received in said end wall channels when the cover members are closed.

4. In a container having side and end walls, each end wall comprising inner and outer layers and the inner layer of each end wall having an upper edge portion folded downwardly and then upwardly to join the upper edge of the outer layer and provide an upwardly opening channel between the two layers, there being a slot extending downwardly from the upper edge of the inner layer of each end wall and there being a registering slot formed in the downwardly folding part of each channel, complementary cover members hinged to said side walls and foldable toward one another over the container, side and end flanges on each cover member, and angularly bent corner tongues connecting the side and end flanges, the ends of said side flanges and the tongues being received in the upper edge slots of the end walls and said end flanges being received in said end wall channels when the cover members are closed.

5. In a container having side and end walls, each end wall comprising inner and outer layers and the inner layer of each end wall having an upper edge portion folded downwardly and then upwardly to join the upper edge of the outer layer

and provide an upwardly opening channel between the two layers, there being a slot extending downwardly from the upper edge of the inner layer of each end wall and there being a registering slot formed in the downwardly folding part of each channel, complementary cover members hinged to said side walls and foldable toward one another over the container, side and end flanges on each cover member, the ends of said side flanges being received in the upper edge slots of the end walls and said end flanges being received in said end wall channels when the cover members are closed, and metal staples securing said end wall layers and channel-forming parts in assembled position so that the channels frictionally aid in maintaining the cover end flanges in position when the cover members are closed.

6. In a container having a bottom provided with end flaps and having side walls provided with end flaps, end walls for the container, each end wall comprising inner and outer layers between which the end flaps of the bottom and side walls of the container are received, the inner layer of each end wall having an upper edge portion folded downwardly and then upwardly to join the upper edge of the outer layer and provide an upwardly opening channel between the two layers, there being a fold line between said downwardly and upwardly folded channel-forming parts with slots in the ends of said fold line for receiving upper end portions of the side wall end flaps, complementary cover members hinged to said side walls and foldable toward one another over the container, and end flanges on each cover member, said cover end flanges being received in said end wall channels when the cover members are closed.

7. In a container having a bottom provided with end flaps and having side walls provided with end flaps, end walls for the container, each end wall comprising inner and outer layers between which the end flaps of the bottom and side walls of the container are received, the inner layer of each end wall having an upper edge portion folded downwardly and then upwardly to join the upper edge of the outer layer and provide an upwardly opening channel between the two layers, there being a fold line between said downwardly and upwardly folded channel-forming parts with slots in the ends of said fold line for receiving upper end portions of the side wall end flaps, there being a slot extending downwardly from the upper edge of the inner layer of each end wall and there being a registering slot formed in the downwardly folded part of each channel, complementary cover members hinged to said side walls and foldable toward one another over the container, side and end flanges on each cover member, the ends of said cover side flanges being received in the upper edge slots of the end walls, and said cover end flanges being received in said end wall channels when the cover members are closed.

8. In a container having a bottom provided with end flaps and having side walls provided with end flaps, end walls for the container, each end wall comprising inner and outer layers between which the end flaps of the bottom and side walls of the container are received, the inner layer of each end wall having an upper edge portion folded downwardly and then upwardly to join the upper edge of the outer layer and provide an upwardly opening channel between the two layers, there being a fold line between said downwardly and upwardly folded channel-forming parts with

slots in the ends of said fold line for receiving upper end portions of the side wall end flaps, there being a slot extending downwardly from the upper edge of the inner layer of each end wall and there being a registering slot formed in the downwardly folded part of each channel, complementary cover members hinged to said side walls and foldable toward one another over the container, side and end flanges on each cover member, the ends of said cover side flanges being received in the upper edge slots of the end walls, and said cover end flanges being received in said end wall channels when the cover members are closed, metal staples at the ends of each channel extending through the inner and outer end wall layers, 15 through the channel-forming portions, and

5 10

through the upper ends of the side wall end flaps, and metal staples for securing the side and bottom wall end flaps in position between the layers.

9. In a container having side and end walls, each end wall comprising inner and outer layers and the inner layer of each end wall having an upper edge portion folded downwardly and then upwardly to join the upper edge of the outer layer and provide an upwardly opening channel between the two layers, a cover member hinged to the upper edge of at least one of the side walls and foldable over the container, and end flanges on said cover member which are received in said end wall channels when the cover is closed.
